(57) **CLAIM**

The ornamental design of a towel bar, as shown and described.

DESCRIPTION

FIG. 1 is a front perspective view of a towel bar showing the design of variable length according to a first embodiment; FIG. 2 is a front view thereof; FIG. 3 is a rear view thereof; FIG. 4 is a top view thereof; FIG. 5 is a bottom view thereof; FIG. 6 is a right side view thereof; FIG. 7 is a left side view thereof; FIG. 8 is a front perspective view of a towel bar showing the design of variable length according to a second embodiment; FIG. 9 is a front view thereof; FIG. 10 is a rear view thereof; FIG. 11 is a top view thereof; FIG. 12 is a bottom view thereof; FIG. 13 is a right side view thereof; and, FIG. 14 is a left side view thereof.

Shading is used in the drawings to better illustrate the design. The features shown in broken lines depict environmental subject matter only and form no part of the claimed design. The towel bar is shown with a symbolic break in its length. The appearance of any portion of the article between the break lines forms no part of the claimed design.
